US0D1114071S

(12) **United States Design Patent** (10) Patent No.: **US D1,114,071 S**
(45) Date of Patent: ** Feb. 17, 2026

(54) **GAMING MACHINE**(71) Applicant: **AGS LLC**, Las Vegas, NV (US)(72) Inventors: **Karl Frederick Zedell, Jr.**, Johns Creek, GA (US); **Benjamin Martin**, San Francisco, CA (US); **Carlos Martin Terminel Iberri**, San Jose, CA (US); **Daniel Kendall Harden**, Carmel-by-the-Sea, CA (US); **Zack Stephanick**, San Francisco, CA (US); **James Ely Tillery**, Tucker, GA (US); **Kevin Hohman**, North Las Vegas, NV (US); **Parry Staley**, Decatur, GA (US); **Matthew Rodgers**, Cumming, GA (US)(73) Assignee: **AGS LLC**, Las Vegas, NV (US)(**) Term: **15 Years**(21) Appl. No.: **29/948,052**(22) Filed: **Jun. 19, 2024****Related U.S. Application Data**

(63) Continuation of application No. 29/835,493, filed on Apr. 19, 2022, now Pat. No. Des. 1,032,723.

(51) **LOC (15) Cl.** ..... **21-03**(52) **U.S. Cl.**USPC ..... **D21/369**(58) **Field of Classification Search**
